DESIGN FOR A VEGETABLE CRisper PAN OR THE LIKE

Richard B. Janes, Detroit, and Oscar E. Norberg,
Greenville, Mich., assignors to Gibson Electric Refrigerator Corporation, Greenville, Mich., a corporation of Michigan

Application January 18, 1940, Serial No. 89,551

Term of patent 7 years

To all whom it may concern:

Be it known that we, Richard B. Janes and Oscar E. Norberg, citizens of the United States, and residents of Detroit, in the county of Wayne and State of Michigan, and Greenville, in the county of Montcalm and State of Michigan, respectively, have invented a new, original, and ornamental Design for a Vegetable Crisper Pan or the like, of which the following is a specification, reference being had to the accompanying drawing, forming a part thereof.

In the drawing:

We claim:

The ornamental design for a vegetable crisper pan or the like, as shown.

RICHARD B. JANES.
OSCAR E. NORBERG.
